UNITED STATES PATENT OFFICE

WILLIAM K. EBEL, OF CLEVELAND, AND LESSITER C. MILBURN, OF WICKLIFFE, OHIO, ASSIGNORS TO THE GLENN L. MARTIN COMPANY, OF CLEVELAND, OHIO, A CORPORATION OF OHIO

ADJUSTABLE STABILIZER AND FIN

Application filed July 19, 1928. Serial No. 293,937.

This invention relates to an airplane, being more particularly directed to the stabilizer and fin construction of the empennage or tail assembly thereof.

5 The tail assembly of airplanes includes a vertical fin for the purpose of steadyng the rear end of the fuselage in straight flight and preventing too rapid side movement thereof when the rudder is manipulated, and since 10 in planes using a single engine or multiple engines it is necessary to compensate for engine torque, it has heretofore been customary to adjust the vertical fin or fins prior to flight. In addition to the vertical fin or fins, 15 the tail assemblies of airplanes are also provided with horizontal stabilizers serving the purpose of a steadyng member and balancing the plane which might be tail or nose heavy. Although these stabilizers, in many 20 types of planes, are fixed, being set at zero angle and provided with a double-cambered surface having no lift, it is obvious that adjustment of the stabilizer is desirable since, if the plane is tail heavy, the angle of incidence of the stabilizer may be set to secure 25 a positive lift during flight, or, if the plane is nose heavy, it may be set at a negative angle so the tail will be held down during flight.

It is often the case that because of varying 30 load or other conditions it is desirable to change or adjust the angle of incidence of the stabilizer during flight, and because of such desirability the stabilizers of certain 35 types of planes have been adjustably constructed. Heretofore, these adjustable stabilizers have been arranged so that adjustment is secured by raising or lowering the leading edge of the stabilizers, the trailing edge thereof being hinged to the tail assembly. In adjusting this type of stabilizer considerable effort of operation is required because of the loads imposed upon the stabilizer 40 during flight, for which reason this form of construction has not proven entirely satisfactory.

Another disadvantage lies in the fact that such an adjustable stabilizer construction requires the forward truss system to move or float up and down as the leading edge of the 45 stabilizer is raised or lowered and since in

large airplanes having two or more fins and rudders the fins are usually attached to the movable stabilizer, a weak structure results which is subject both to play and fluttering in its moving parts. In attempting to overcome such disadvantages and secure the required strength rigid and cumbersome structures have been designed which create added resistance and excessive weight.

55 Therefore, the principal object of the present invention is to provide a construction for the stabilizer and fin of an airplane tail assembly wherein either or both the stabilizer or fin has the major part thereof fixed with respect to the tail assembly and supported 60 by a fixed truss system, but at the same time, the fin or stabilizer may be readily and independently adjusted during flight so as to provide various lift reactions for the former and 65 adjustments of the latter to compensate for 70 engine torque or other conditions.

Another object is to provide a fin and stabilizer construction for an airplane wherein the effective camber of these members may be 75 adjusted during flight from the cockpit of the plane by simplified mechanism requiring a minimum of effort.

Another object is to provide a strong and rigid, yet simple and light, tail assembly construction for an airplane which includes an 80 adjustable fin and an adjustable stabilizer.

Additional objects and advantages will become apparent as the description of a preferred embodiment of the invention proceeds.

85 In carrying out the objects of the invention, it is contemplated to construct the vertical fin and horizontal stabilizer of an airplane tail assembly of two portions; the rear portion of each member forming the major part thereof and being fixed relative to the tail assembly, while the forward portion forms substantially only the leading edge part thereof and is hingedly connected to the other portion to move through a small angular displacement.

90 An embodiment of the invention is illustrated in the accompanying drawings wherein:

95 Fig. 1 is a fragmentary side elevation of the tail assembly of an airplane fuselage;

Fig. 2 is a section taken approximately on line 2—2 of Fig. 3, the dotted line portions of said figure illustrating diagrammatically the angular displacement of the elevator and of the leading edge portion of the stabilizer;

Fig. 3 is a plan view showing the tail assembly of the plane;

Fig. 4 is a section taken approximately on line 4—4 of Fig. 1, the dotted line portions of said figure illustrating diagrammatically the angular displacement of the rudder and the leading edge portion of the fin;

Fig. 5 is a side elevation of the airplane fuselage, the outlines of the fuselage being indicated by dot and dash lines, and the tail assembly thereof together with its operating mechanism being indicated in full lines;

Fig. 6 is an enlarged elevational view of the chain and sprocket mechanism which is installed in duplicate in the airplane cockpits for operating the adjustable leading edge portion of the stabilizer and fin; and

Fig. 7 is a rear elevation of the tail surfaces of the plane.

The fuselage 10 of the plane may be of any desired construction and provided at its forward portion with one or more cockpits 11. The tail assembly of the plane includes the usual rudder 12 and the vertical fin arranged forwardly of the rudder, which fin has a fixed portion 13 and a movable leading edge portion 14 pivotally connected adjacent to its rear edge to the forward edge of the fixed portion. The tail assembly also includes the elevators 15, forwardly of which is the horizontal stabilizer comprising a fixed portion 16 and a movable leading edge portion 17. It should be noted that the fixed portion of both the vertical fin and stabilizer constitutes

the major part of the respective members, while the movable portion of each constitutes, in effect, merely the leading edge portion, and it is because of this fact that the effort of operation in the adjustment of the movable portion of these members is reduced to a minimum and the strength of the tail assembly is not weakened. The movable portion of the stabilizer is pivotally mounted adjacent its rear edge upon a horizontally extending pivot 18, while its forward edge is operatively connected with an operating or adjusting screw 19 adapted to move such edge upwardly or downwardly as the case may be. The forward edge of the portion 16 of the stabilizer is concaved so that the convex or rounded rear edge of the movable portion 17 thereof may be free to move to its various positions of adjustment, a slight clearance being also provided between the fixed and

movable portions of the stabilizer to insure freedom of such movement. It should be observed that when the movable and fixed portions of the stabilizer are arranged in the position indicated in Fig. 1 that the forward edge of the stabilizer unit including these

portions is, in effect, merely a cambered surface and that no positive lift or depressing action of the stabilizer will take place.

The operating or adjusting screw 19 is rotatably mounted in bearings 20 secured to the side of the fuselage and is connected at its upper end to the forward edge of the movable portion of the stabilizer by a link 21. Interposed between the two lower bearings 20 is a hub member 22 having internal threads engaging with the external threads upon the screw 19 and being provided exteriorly with a sprocket wheel 23 rigidly secured thereto and adapted to be turned by means of an operating chain, not numbered, which is connected to operating cables 24 and 25. It is thus apparent that when the cables 24 and 25, and, in turn, the operating chain, are moved in opposite directions, that the sprocket 23 and the hub 22 will be correspondingly rotated, thereby causing the shaft 19 to move upwardly or downwardly in its bearings, as the case may be, and, in turn, raising or depressing the leading edge of the movable portion 17 of the stabilizer.

The leading edge of the fixed portion 13 of the vertical fin is concaved in the same manner as the leading edge of the fixed portion 16 of the stabilizer, while the rear edge of the movable portion 14 of the fin is convexed similarly to the corresponding edge of the portion 17 of the stabilizer, the objects and advantages of this arrangement having been fully set forth with respect to the stabilizer.

The movable portion 14 of the fin is operated by means of a screw shaft 26 rotatably carried in bearings 27 and 28 and connected by a linkage 29 to a bracket 30 carried by the lower end of such portion of the fin. An internally threaded hub 31 is arranged on the shaft between the bearings 27 and 28, which hub carries a sprocket wheel 32 engaged by a chain 33. This chain is connected at its opposite ends to the operating cables 34 and 35 in the same manner as the chain which encircles the sprocket 23 is connected to the cables 24 and 25. Since the manner in which all of the cables, namely, 24, 25, 34 and 35 are connected to the operating mechanism is the same, it will only be necessary to describe the connection between such operating mechanism and the cables 34 and 35, it being understood that the same applied also to the cables 24 and 25 and to the operating mechanism therefor.

Sprockets 36 and 37 are rotatably mounted adjacent each of the cockpits 11, being operated by means of the cranks 38 and 39. A chain 40 surrounds the sprocket 36 and a chain 41 surrounds the sprocket 37, the free ends of each of these chains being connected to connecting links 42 and 43, to which links are connected the forward ends of the cables 34 and 35. It is thus apparent that when

either of the cranks 38 and 39 is rotated in the desired direction, that the chains 40 and 41 will move around the sprockets 36 and 37 and, in turn, will move the cables 34 and 35, thus transmitting the movement through the chain 33 to the sprocket 32 and causing adjustment of the vertical fin to be effected. However, in order to limit the movement of the cables and, in turn, the adjustment of the fin, stops 44 and 45 are rigidly connected to the cables 34 and 35 by soldering or otherwise, and these stops are adapted to contact with the guides or floor leads 46 carried by the fuselage and through which the cables pass. As already pointed out, the cables 24 and 25 which are operatively connected to the adjusting or operating screw 19 for the horizontal stabilizer, are operatively connected in the same manner by chains 47 and 48 which encircle the sprockets 49 and 50 likewise arranged adjacent to each cockpit. It should be understood that in the case of a single cockpit only one operating sprocket would be required and that the connection would be changed accordingly.

The construction just described provides for easy adjustment of the fin and stabilizer from both of the cockpits and, therefore, enables the pilot to make such adjustments as may become necessary during flight. The operating mechanisms for adjusting the rudder and elevators have not been shown since the same may take the form of any preferred construction, while the struts and wires used to rigidly brace the fixed portion 16 of the stabilizer are indicated at 51, 52 and 53, respectively. In Figs. 3 and 7 extra fins 54 and extra rudders 55 have been indicated, such extra members being used in the case of multi-engine planes.

Although a preferred embodiment of the invention has been illustrated and described, it should be understood that the invention is not to be limited thereto but may take such modifications and variations within the scope of the following claims and that the specific operating mechanism for the fin and stabilizer may take various forms, the one shown being simply for purposes of illustration.

Having thus described our invention, we claim:

1. An airplane construction comprising in the tail assembly thereof a vertical fin, said fin being formed of two parts hingedly connected together, the rearward of said parts being fixed with respect to the tail assembly and the forward of said parts being movable thereto.

2. An airplane construction comprising in the tail assembly thereof a vertical fin, said fin being formed of two parts, the rearward one of which includes substantially the major portion of the fin and is fixed with respect to the tail assembly, while the forward one of which includes substantially the lead-

ing edge portion of the fin and is adjustably mounted with respect to the tail assembly and to the other part of the fin.

3. An airplane construction comprising in the tail assembly thereof a horizontal stabilizer, said stabilizer being formed of a plurality of parts, one of which is fixed in relation to said assembly and another of which is movable in respect to said fixed parts; the forward edge portion of said fixed part and the rear edge portion of a forward part being nested together in faired relation.

4. An airplane construction comprising in the tail assembly thereof a horizontal stabilizer, said stabilizer being formed of two parts hingedly connected together in faired relation, the rearward of said parts being fixed with respect to the tail assembly and the forward of said parts being movable with respect thereto.

5. An airplane construction comprising in the tail assembly thereof a horizontal stabilizer, said stabilizer being formed of two parts, the rearward one of which includes substantially the major portion of the stabilizer and is fixed with respect to the tail assembly, while the forward one of which includes substantially the leading edge portion of the stabilizer and is adjustable with respect to said major portion, the rear edge portion of said leading edge portion nested in faired relation with the forward edge portion of said major portion.

6. An airplane construction comprising in the tail assembly thereof in combination a vertical fin and a horizontal stabilizer, said fin and said stabilizer each being formed of two parts, the rearward of which constitutes the major portion of its respective member and is fixed relative to the tail assembly, and the forward part of which forms substantially the leading edge portion of its respective member and is hingedly mounted to move through an angular displacement with respect to the other part and the tail assembly.

7. An airplane construction comprising a tail assembly including a vertical fin, said fin being formed of two parts, the rearward one of which includes substantially the major portion of the fin and is fixed with respect to the tail assembly, while the forward one of which includes substantially only the leading edge portion of the fin and is adjustably mounted with respect to the tail assembly and to the other part of the fin, and means associated with said forward part of the fin and adapted to be operated from the cockpit of the plane for effecting adjustment thereof.

8. An airplane construction comprising a tail assembly including a horizontal stabilizer, said stabilizer being formed of two parts arranged in faired relation to each other, the rearward one of which includes substantially the major portion of the stabilizer and is fixed with respect to the tail as-

- sembly, while the forward one of which includes substantially only the leading edge portion of the stabilizer and is adjustable with respect to the tail assembly and the 5 other part, and means adapted to operation from the cockpit for changing the streamlining relation between said parts to a cambered relation therebetween.
9. An airplane construction comprising a 10 tail assembly including, in combination, a vertical fin and a horizontal stabilizer, said fin and said stabilizer each being formed of two parts, the rearward of which constitutes the major portion of its respective member 15 and is fixed relative to the tail assembly and the forward part of which forms substantially only the leading edge portion of its respective member and is hingedly mounted to move through an angular displacement 20 with respect to the other part and to the tail assembly, and independent means associated with the forward part of both the fin and the stabilizer and adapted to be operated from the cockpit of the plane for effecting 25 adjustment thereof.
10. An airplane comprising a tail assembly including a vertical fin, said fin being formed of two parts, the rearward of which is fixed with respect to the tail assembly and the forward of which is adjustable with respect thereto, an operating member associated with said forward adjustable part of the fin, actuating means arranged adjacent to the cockpit of the plane, and an operative 30 connection between said operating member and said actuating means whereby said adjustable part of the fin may be moved through an angular displacement.
11. An airplane comprising a tail assembly 40 including a horizontal stabilizer, said stabilizer being formed of two parts arranged in paired relation to each other the rearward of which is fixed with respect to the tail assembly and the forward of which is angularly movable with respect to said fixed part thereto, an operating member associated with said forward part of the stabilizer, actuating means arranged adjacent to the cockpit of the plane, and an operative 45 connection between said operating member and said actuating means whereby said movable part of said stabilizer can be angularly displaced in relation to said fixed part thereby creating variable stabilization.
12. An airplane comprising a tail assembly 55 including, in combination, a vertical fin and a horizontal stabilizer, each of said members having a rearward fixed part forming substantially the major portion of its respective member and a forward adjustable part forming substantially only the leading edge portion of its respective member, an operating member associated with the forward adjustable part of each of said first 60 named members, independent actuating 65 means for each of said operating members arranged adjacent to the cockpit of the plane, and an operative connection between each of said operating members and its respective actuating means whereby the fin and stabilizer may be adjusted.
13. An airplane construction combining in the tail section thereof a vertical fin comprising two main parts, one of said parts fixed in relation to said section and the other 70 of said parts hingedly movable in front angular relation to said fixed part, and a rudder hingedly movable in rear angular relation to the fixed part of said fin.
14. An airplane construction combining 75 in the tail section thereof a vertical fin comprising two main parts, one of said parts fixed in relation to said section and the other of said parts hingedly movable in front angular relation to said fixed part, a rudder hingedly movable in rear angular relation to the fixed part of said fin, and means in the cockpit cooperating with means connected in operative relation to said movable part of said fin whereby said angular relations may be controlled therefrom.
15. An airplane construction combining 80 in the tail section thereof a horizontal stabilizer comprising two main parts, one of said parts fixed in relation to said section and the other of said parts hingedly movable in front angular relations to said fixed part, said parts faired in nested endwise relation to each other, and an elevator hingedly movable in rear angular relation to the fixed part 85 of said stabilizer.
16. An airplane construction combining 90 in the tail section thereof a horizontal stabilizer comprising a major and a minor main part, the major of said parts fixed in relation to said section and the minor of said parts hingedly movable in front angular relation to said fixed part, said parts faired in nested endwise relation to each other, an elevator hingedly movable in rear angular relation to 95 the major part of said stabilizer, and means in the cockpit cooperating with means connected in operative relation to said movable part whereby said angular relation may be controlled therefrom.
17. An airplane construction comprising 100 in the tail assembly thereof a vertical fin, said fin being formed of two parts, the rearward of said parts being fixed in relation to said assembly and the forward of said parts hinged in relation to said rearward part and said assembly; the forward edge portion of said fixed part and the rearward edge portion of said hinged part being nested together in faired relation.
18. An aircraft construction comprising 110 in the tail assembly thereof a vertical fin, said fin being formed of three parts hingedly connected together in tandem relation; the intermediate of said parts being fixed in rela- 115
- 120
- 125
- 130

tion to both of said hinged parts; and the contiguous edge portions of said fixed part and of said forward part nested each with the other.

- 5 19. An airplane construction comprising in the tail assembly thereof a horizontal stabilizer, said stabilizer being formed of two parts, the rearward of said parts being fixed in relation to said assembly and the forward 10 of said parts hinged in relation to said rearward part and said assembly; the forward edge portion of said fixed part and the rear edge portion of said hinged part being nested together in faired relation.
- 15 20. In an aircraft, a horizontal stabilizer comprising a minor forward portion, and a major rear portion fixed with respect to said aircraft; said minor portion hinged in nested relation to said major portion; said minor 20 portion and said major portion adapted by their cooperative contours to form a streamlined stabilizer when adjusted in tandem relation and to form a cambered stabilizer when adjusted in angular relation; means for 25 adjusting said portions to either of said relations.
- 21. In an aircraft, a horizontal stabilizer comprising a minor forward portion, and a major rear portion fixed with respect to said 30 aircraft; said minor portion hinged in nested relation to said major portion, said portions being in streamlined relation when said minor portion is adjusted in tandem with said major portion and in cambered relation 35 when said minor portion is angularly adjusted to said fixed portion; and means adapted to operation from the cockpit for adjusting said movable portion from a streamlining relation to a cambering relation with said 40 fixed portion.
- 22. In an aircraft stabilizing system, a stabilizing member in which a minor forward portion is hinged in endwise nested faired relation to a major portion, said major portion 45 fixed in relation to a supporting structure; a dual remote control mechanism for said hinged part; said mechanism comprising a sprocket wheel and an associated screw shaft adapted to adjust said minor part in angular 50 relation to said major part, a sprocket chain adapted to rotate said wheel, a second and a third sprocket wheel spaced apart in tandem relation and operatively attached to said structure; said second and third sprocket 55 wheels coaxially rotatable by a second sprocket chain, the ends of said first chain operatively connected with said second chain intermediate said second and third sprockets, and a crank for each of said second and 60 third sprockets for manual operation of said system.

In testimony whereof, we hereunto affix our signatures.

WILLIAM K. EBEL.
LESSITER C. MILBURN.
